CLAIM

We claim the ornamental design for a luminaire and luminaire assembly, as shown and described.

DESCRIPTION

FIG. 1 is a first perspective view of a luminaire according to a new design.

FIG. 2 is a second perspective view of the luminaire of FIG. 1.

FIG. 3 is a first plan view of the luminaire of FIG. 1 illustrating a light emitting surface.

FIG. 4 is a second plan view of the luminaire of FIG. 1.

FIG. 5 is a front view of the luminaire of FIG. 1.

FIG. 6 is a rear view of the luminaire of FIG. 1.

FIG. 7 is a first side elevation view of the luminaire of FIG. 1; and,

FIG. 8 is a second side elevation view of the luminaire of FIG. 1.

The broken lines illustrate portions that form no part of the claimed design.

1 Claim, 3 Drawing Sheets
